UNITED STATES PATENT OFFICE.

ALBERT JAMES POTEET, OF LAKELAND, FLORIDA.

WINDOW-SHADE FIXTURE.

956,731.

Specification of Letters Patent.

Patented May 3, 1910.

Application filed October 6, 1909. Serial No. 521,263.

To all whom it may concern:

Be it known that I, ALBERT JAMES POTEET, a citizen of the United States, residing at Lakeland, in the county of Polk and State 5 of Florida, have invented a new and useful Window-Shade Fixture, of which the following is a specification.

It is the object of this invention to provide a window shade fixture, adapted to 10 support shade rollers for rotation, the device being so constructed that, as the shade is rolled upon the roller, the shade, owing to the construction of the fixture, will be wound smoothly and evenly upon the roller; 15 and, with this end in view, the invention consists in a window shade fixture fashioned from a single piece of metal and bent, and slotted, to form arms, which are adapted to serve as guides for the shade as it is wound 20 up.

Other and further objects will be made manifest hereinafter, as the description of the invention progresses.

The drawings show but one form of the 25 invention, and it is to be understood that changes, properly falling within the scope of what is claimed, may be made, without departing from the spirit of the invention.

Similar numerals of reference are employed 30 to denote corresponding parts throughout the several figures of the drawings, wherein:

Figure 1 is a perspective showing the device applied; Fig. 2 is a side elevation; Fig. 3 is an end elevation; Fig. 4 is a top plan.

The improved window shade fixture forming the subject matter of this application, is fashioned from a single piece of flat metal, comprising a base 1, provided with openings 2, or otherwise adapted to receive support 35 engaging means. The base 1 is provided with an integrally formed arm 3, outstanding from the inner edge of the base, in a plane substantially normal to the plane of the base, the arm being provided with an integrally formed lip 5, depending from the 40 lower edge of the arm 3, in a common plane with the arm, the lip being bent inwardly to dispose its end in a plane substantially normal to the plane of the arm and of the lip, the said end of the lip being slotted, 45 throughout a portion of its length, as denoted by the numeral 6, to form arms 7, between which the edges of the shade are adapted to move, when the shade is wound 50 upon the roller. The end of the lip is provided, at the edge of the slotted portion 6,

with a rounded flange 8, which is adapted to prevent the curtain from being worn as it passes between the arms 7. In the lower edge of the arm 3, there is fashioned a flaring notch 9, located between the base 1 and the lip 5, one edge of the notch being defined by the edge of the lip. 60

In the drawings, the extremity of the arm 3 is apertured, as denoted by the numeral 4, 65 to receive and to hold for rotation, the round trunnion which is mounted in one end of the shade roller.

It is to be understood that the invention is to be fashioned in pairs, and that the other 70 member of the pair will be provided with a notch, in which the square trunnion which is mounted in the other end of the roller, will be secured against rotation. These 75 details are common in the art to which my invention appertains and I see no necessity of delineating specifically, both of the brackets, their construction being substantially identical, saving in so far as hereinbefore pointed out. 80

Under ordinary conditions, a screw or like element will be passed through the openings 2 in the base 1 to support the device upon the window frame. It may, however, be desired to use a staple tack in mounting the device, and, in such case, the notch 9 is adapted to receive a staple tack, the staple tack being firmly wedged in the notch 9 as shown, and the upper extremity of the base 1 being secured to the window frame in any desired 90 manner. By this construction, when it is desired to remove the shade fixture from the window, the upper fastening only need be removed, the fixture being then lifted from the staple tack which is engaged by the 95 notch 9.

From the foregoing it will be seen that I have provided a window shade fixture which is adapted to be mounted securely upon a window frame and to be removed readily 100 and quickly therefrom, the fixture being so constructed, that as the shade is wound upon the roller or unwound therefrom, the shade will be received between the arms 7 and properly aligned as it moves upwardly or 105 downwardly, notably, as it moves upwardly to be wound upon the shade roller.

Having thus described the invention, what is claimed is:

1. A shade fixture fashioned from a single 110 piece of flat metal and comprising a base adapted to receive support engaging means,

the base being provided with an integrally formed arm outstanding from the inner edge thereof in a plane substantially normal to the plane of the base and adapted to receive 5 a shade support, the arm being provided with an integrally formed lip, depending from the lower edge of the arm in a common plane with the arm, the lip being bent inwardly to dispose its end in a plane substantially normal to the plane of the arm and lip, said end being slotted throughout a portion of its length to form spaced, shade receiving arms. 10

2. A shade fixture fashioned from a single 15 piece of flat metal and comprising a base adapted to receive support engaging means, the base being provided with an integrally formed arm outstanding from the inner edge thereof in a plane substantially normal to the plane of the base and adapted to receive 20 a shade support, the arm being provided with an integrally formed lip, depending from the lower edge of the arm in a common plane with the arm, the lip being bent inwardly to dispose its end in a plane substantially normal to the plane of the arm and lip, said end being slotted throughout a portion of its length to form spaced, shade receiving arms, there being a rounded flange 25 upon the end of the lip, at the edge of the slotted portion thereof.

3. A shade fixture fashioned from a single 30 piece of flat metal and comprising a base adapted to receive support engaging means, the base being provided with an integrally 35 formed arm outstanding from the inner edge thereof in a plane substantially normal to the plane of the base and adapted to receive

a shade support, the arm being provided with an integrally formed lip, depending 40 from the lower edge of the arm in a common plane with the arm, the lip being bent inwardly to dispose its end in a plane substantially normal to the plane of the arm and lip, said end being slotted throughout 45 a portion of its length to form spaced, shade receiving arms, there being a flaring notch in the lower edge of the first named arm between the base and the lip.

4. A shade fixture fashioned from a single 50 piece of flat metal and comprising a base adapted to receive support engaging means, the base being provided with an integrally formed arm outstanding from the inner edge thereof in a plane substantially normal to 55 the plane of the base and adapted to receive a shade support, the arm being provided with an integrally formed lip, depending from the lower edge of the arm in a common plane with the arm, the lip being bent inwardly to dispose its ends in a plane substantially 60 normal to the plane of the arm and lip, said end being slotted throughout a portion of its length to form spaced, shade receiving arms, there being a rounded flange upon the 65 end of the lip at the edge of the slotted portion thereof and the first named arm being provided, in its lower edge, between the base and the lip, with a flaring notch.

In testimony that I claim the foregoing as 70 my own, I have hereto affixed my signature in the presence of two witnesses.

ALBERT JAMES POTEET.
